ICE PICK

Filed Dec. 14, 1925

WITNESS:

Hugo C. Asmus,
INVENTOR
BY Victor J. Evans

ATTORNEY

UNITED STATES PATENT OFFICE.

HUGO CARL ASMUS, OF KANSAS CITY, MISSOURI.

ICE PICK.

Application filed December 14, 1925. Serial No. 75,428.

The object of this invention is to provide a safety ice pick, in which the pointed element shall be slidable into the handle portion, said handle portion being provided with a blade or the like permanently affixed thereto, and constituting an ice chipping device.

A further object is to provide particular means for retaining the pointed element in either operative or inoperative position.

A further object is to provide a device which shall include a handle having a longitudinal bore and a ferrule with an ice chipping element formed integrally therewith, the ferrule being applied to the handle in the usual manner, and the chipping blade being offset to permit of the mounting of the pointed element centrally of the handle and within the longitudinal bore thereof.

In the drawings forming part of this application,

Figure 1 shows the device in elevation, when in operative position.

Figure 2 is a view in vertical section.

Figure 3 is a perspective view of the awl-like element constituting the working portion of the pick.

Figure 4 is a detail view showing the awl-like element in its retracted position.

The handle 10 may have an enlargement 11 at the upper end thereof, and said handle is provided with a longitudinal or vertical bore 12 extending for nearly the full length.

A ferrule 13 is mounted on a reduced portion 14 at the end of the handle, and formed integrally with the ferrule 13 is an ice chipping element, including a shank 15 and a blade 16, the latter having a working edge, such as that shown at 17.

The handle 10 is also formed with a longitudinal slot 18 having communication with the bore 12 and having an offset end 19, and another offset end 20, it being noted that the slot is continued through the ferrule 13 and that the offset end of the slot in the handle registers with a similar offset slot 22 in the ferrule.

The awl-like member, or pick per se, is designated 24, and is provided with a point 25 and with an end portion 26 having secured thereto an operating and engaging member comprising a shank 27 having rectangular or angular cross section and a knob or the like such as 28. The shank 27 is proportioned to fit within the slot 18, and is

movable in the offset portions 19, 20 and 22, the upper end 26 of the element 24 being of substantially the same cross section as the bore 12, and the awl-like member being slideable within the bore, and being adapted to be secured in operative position as shown in Figure 1, or to be withdrawn into the bore, so that it will be inoperative for use as an ice-pick, but the chipping blade 17 may then be employed.

An important feature of the construction is that the element 24 is so proportioned, and the engaging device 27 is so placed with reference to the offset ends 19 and 20 of the slot 18, that the sharp end 25 of element 24 will be opposite the middle portion of blade 16, or approximately in that position, so that element 16 acts as a guard, preventing injury by the pointed end of element 24.

Having thus described the invention, what is claimed as new is:

1. A device of the class described, comprising a handle having a longitudinal bore and having a longitudinal slot communicating with the bore, a tool slideable within the bore, and a shield member offset from the end of the handle and extending longitudinally thereof and over the free end of the tool when the latter has reached its limit of retractive movement in the bore.

2. A device of the class described, comprising a handle having a longitudinal bore, a blade connected with one end of the handle, the bore being open at the corresponding end of the handle, a tool slideable in the bore and movable alongside of the blade, and beyond the cutting edge thereof, the handle and blade maintaining a fixed relation, and means for retaining the slideable tool in an operative position and in an inoperative position.

3. A device of the class described, comprising a handle having a longitudinal bore, a ferrule carried by the handle, a blade carried by the ferrule and projecting from the handle in offset relation to the bore, a tool slideable in the bore and alongside of the blade, means for retaining the tool in retracted position within the handle, or in a position projecting from the end thereof, alongside of the blade, the blade acting as a guard for the tool in its retracted position.

In testimony whereof I affix my signature.

HUGO CARL ASMUS.
